PORTABLE LOUNGE SEAT

Bruce S. Martin, 2224 N. Puget Sound,
Tacoma, Wash. 98406

Filed Jan. 19, 1970, Ser. No. 20,978

Term of patent 14 years

Int. Cl. D6—02

U.S. Cl. D15—8

FIG 1

FIG 2

FIG 3

FIG 4

FIG 5

FIG 6

FIG 7

FIG. 1 is a front perspective view of my new design of a portable lounge seat in one of its lounge positions; FIG. 2 is a back perspective view, thereof, in its lounge position;

FIG. 3 is a front view, thereof, in the ottoman position; FIG. 4 is a back view, thereof, in the ottoman position;

FIG. 5 is a side view, thereof, in the ottoman position, the opposite side being similar;

FIG. 6 is a top view, thereof, in the ottoman position; and

FIG. 7 is a bottom view, thereof, in the ottoman position.

I claim:

The ornamental design for a portable lounge seat, as shown and described.
